(No Model.)

A. T. CROSS.

CRAYON HOLDER.

No. 296,537.

Patented Apr. 8, 1884.

UNITED STATES PATENT OFFICE.

ALONZO T. CROSS, OF PROVIDENCE, RHODE ISLAND.

CRAYON-HOLDER.

SPECIFICATION forming part of Letters Patent No. 296,537, dated April 8, 1884.

Application filed August 15, 1883. (No model.)

To all whom it may concern:

Be it known that I, ALONZO T. CROSS, of Providence, in the State of Rhode Island, have invented an Improvement in Crayon-Holders, 5 of which the following is a specification.

My invention relates to an improvement in that class of crayon-holders in which a forceer is employed for automatically ejecting the unused stub of the crayon from the carrier-tube; 10 and it consists in the combination of a carrier-tube, provided with a split end for frictionally holding the crayon, with a spring arranged to intervene between the forceer and the rear end of the crayon, whereby the holding-stub of a 15 used-up crayon may at the proper time be automatically thrown to a considerable distance by means of the resilience of the spring.

Figure 1 represents an axial section of a crayon-holder having a carrier provided with 20 my improved forceer-spring. Fig. 2 is an elevation of the slotted screw-holding tube. Fig. 3 is an elevation of the carrier-tube with an inserted crayon. Fig. 4 represents the several 25 parts of the screw mechanism as secured to each other preparatory to the final attachment of the case of the holder. Fig. 5 is an axial section of the carrier with an inserted crayon. Figs. 6 and 7 represent the application of my 30 improvement to the carrier shown and described in my Patent No. 263,392.

In the accompanying drawings, A is the screw-holding tube, provided longitudinally with a slot, *a*, the lower end of which is made wider than its upper portion to form the 35 shoulder *b*. The lower end of the tube A is provided with the opposite slots *c*, and the two jaws *d* so formed are arranged to spring toward each other, in order to clasp the crayon, and also the lower end of the carrier-tube B 40 when the carrier is brought down to expel the unused stub of the crayon, and upon the tube A, between the slots *a* and *c*, is secured the collar *e*, by means of which the point-tube C is secured to the tube A.

The carrier for the crayon is formed of a 45 tube, B, made to fit loosely within the bore of the tube A, and provided longitudinally at near its upper end with a slot, *f*, the upper portion of which is laterally deflected to form 50 a holding-notch for the pin of the forceer, and

the lower end of the carrier-tube is provided with a split, *r*, for a short distance, in order to adapt the same for receiving crayons of slightly-different diameters.

Within the carrier-tube B is placed the 55 loosely-moving forceer E, provided with the pin *j*, which enters the slot *f*, and, passing through the slot *a* of the tube A, enters the groove *k* of the hollow screw G, which is loosely held upon the tube A by means of the fixed collar *g*. 60 The forward end of the forceer E is provided with a projecting stem, *i*, upon which is placed the spiral spring *h*. The plug F, also moving loosely in the bore of the tube B, is provided with a pin, *m*, which enters the lower portion 65 of the slot *f*, and the spring *h* is made to occupy the space between the plug F and forceer E, as shown in the section, Fig. 1, which represents the forceer and plug at their greatest 70 distance from each other, the pins *j* and *m* being at opposite ends of the slot *f*, which forms a limiting-stop to the movement of the forceer and plug under the action of the intervening spring. When the crayon H is inserted into the split end of the carrier-tube, the plug F 75 will be forced backward, causing the compression of the spring *h* until the stem *i* brings up against the rear end of the plug F, as shown in Fig. 5.

The operation of the holder will be as follows: Upon turning the screw G in the proper direction the crayon will be fed downward to the point *o* of the holder, and when the crayon has been nearly used up the forward end of the carrier will strike the inner side of the conical 85 end *o* of the point-tube C, and also encounter the resistance caused by the spring action of the jaws *d* *d*, which will serve to prevent the carrier-tube B from revolving within the bore of the tube A under the continued movement of 90 the screw, which movement will cause the pin *j* to be moved laterally to a position under the shoulder *b* in the slot of the tube A, and also at the same time out of its retaining-notch *n* in the slot *f* of the carrier-tube, after which 95 the continued movement of the screw will impart a longitudinal movement to the forceer, the pin *j* passing forward along the slot *f*, and the stem *i*, which is in contact with the rear end of the plug F, will serve to impart an equal 100

movement to the plug, tending to force the stub of the crayon out of the carrier-tube; and as the crayon gradually moves forward, the frictional hold upon the same by the spring of the split end of the carrier will become gradually lessened until a point is reached in which the frictional grip will be overcome by the resilience of the spring, which will then cause the sudden ejection of the crayon to a considerable distance from the holder, the forward movement of the plug F being limited by the pin *m* and slot *f*, or by any other suitably-arranged stop. Now, in order to insert a fresh crayon, the movement of the screw is to be reversed and the reverse movement continued until the pin *j* has been brought to the upper end of the slot *f*, and then upon the movement of the pin *j* into the notch *n* the crayon may be inserted into the end of the carrier-tube, thus compressing the spring *h* until the proper degree of insertion has been reached, as shown in Fig. 5, and by the continued movement of the screw the crayon may be drawn wholly within the bore of the holder.

I do not of course limit my claim for a spring arranged between the forcer and the rear end of the crayon to any particular form of mechanism for operating the forcer, since my improvement is applicable to carriers that are differently operated—as, for instance, that shown and described in my Patent No. 263,392, an axial section of which is shown in Fig. 6, with an elevation of the forcer in Fig. 7, the spring *h* being in this case held in the hollow end of the forcer, as shown in Fig. 6, and upon the ejection of the crayon *H* the spring will project beyond the forward end of the forcer, as shown in Fig. 7, and a disk, *p*, may be soldered to the end of the wire spring, in order to protect the same from injury.

My improved forcer-spring may also be adapted to the carriers of ordinary slide-pencils in which the screw mechanism is not employed; and in carrying out my invention in such pencils I prefer to make use of two slides—one secured by pin to the carrier-tube and the other to the forcer—and upon the arrival of the carrier-tube at its stop at the lower end of the pencil the required additional forward movement is to be imparted to the slide of the forcer, and the form of carrier shown in Fig. 6 is adapted for this purpose.

I claim as my invention—

1. In a crayon-holder, the combination of the carrier-tube, provided with a split end for frictionally holding the crayon, with means, substantially as described, for imparting an initial movement to the crayon-stub from the carrier-tube, and a spring for forcibly ejecting the same when the frictional grip of the split end of the tube has become less than the resilience of the spring.

2. In a crayon-holder, the combination of the screw mechanism, and a carrier-tube provided with a split end for frictionally holding the crayon, with a forcer and a spring adapted to forcibly eject the stub of the crayon upon the continued movement of the screw after the carrier has reached its stop at the lower end of the holder.

3. In a crayon-holder, the combination of the screw mechanism, and a carrier-tube provided with a split end for frictionally holding the crayon, with a forcer, a plug, and an intervening spring adapted to forcibly eject the crayon, substantially as described.

ALONZO T. CROSS.
